(57) **CLAIM**

The ornamental design for a cosmetic and therapeutic face mask, as shown and described.

DESCRIPTION

FIG. 1 is a perspective view of a cosmetic and therapeutic face mask showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings are for the purpose of illustrating portions of the cosmetic and therapeutic face mask that form no part of the claimed design.
